(57) **CLAIM**

The ornamental design for a hose clip with lanyard, as shown and described.

DESCRIPTION

FIG. 1 is a perspective view of a hose clip with lanyard, showing my design;

FIG. 2 is a left side view thereof, the right side view being a mirror image;

FIG. 3 is a top view thereof;

FIG. 4 is a bottom view thereof;

FIG. 5 is a front view thereof;

FIG. 6 is a rear view thereof;

FIG. 7 is a front view of the hose clip with the lanyard removed; and,

FIG. 8 is a rear view of the hose clip with the lanyard removed.

The broken lines throughout the Figures show portions of the hose clip with lanyard that form no part of the claimed design.
